SOLEPLATE FOR IRONS AND METHOD FOR
MAKING THE SAMERoy L. Trimble, Bloomington, Ill., assignor to
Eureka Williams Corporation, Bloomington, Ill.,
a corporation of Michigan

Application November 14, 1947, Serial No. 785,870

6 Claims. (Cl. 201—64)

1

This invention relates to electrical heating plates or units such as sometimes are employed as sole plates for irons, grid surfaces for waffle irons, heating elements for electric stoves, etc. The invention also comprises a novel method and an apparatus for manufacturing such plates, grids or elements.

Some of the objects of the invention are:

To provide an electrically insulated electrical resistance element which can be manufactured at relatively low cost, which will have substantially an equal rate of heat transfer in all directions radially outwardly with respect to the electrical resistance wire or member, and which electrically insulated element or unit may be cast or otherwise embedded in a fluid metal body, the extraction of the heat of fusion from which will place the insulating material of the unit under compression so as to provide the best possible thermal contact relation between the resistance element and the body.

Other and further objects of the invention will be apparent from the following description and claims and will be understood by reference to the accompanying drawings, of which there are two sheets, which, by way of illustration, show a preferred embodiment and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims. I also contemplate that of the several different features of my invention, certain ones thereof may be advantageously employed in some applications separate and apart from the remainder of the features.

Referring to the drawings:

Figures 1, 2, 3, 4 and 5 disclose sections of a mold in which an electrical resistance element embracing the principles of the invention is being progressively formed.

Figure 6 is a fragment of the mold in the position shown by Figure 1 except that Figure 6 illustrates a section through a different part of the resistance element being formed.

Figure 7 illustrates a cross-sectional view through a section of the heat insulating sheath, after the formation of the section has been completed and before the resistance member is disposed therein.

Figure 8 is a cross-sectional view through a completed insulated resistance element as the

2

same might appear in a vertical plane through one of the terminals at the end of the unit.

Figure 9 is a view similar to that shown by Figure 8 except that Figure 9 is taken on a vertical plane remote from the terminal ends of the unit.

Figure 10 is a plane view of the completed electrical resistance unit or element.

Figure 11 is an end elevation view of the structure shown in Figure 10.

Figure 12 is a view of a mold in which the unit illustrated by Figures 10 and 11 is supported in position for casting the same in molten or fluid metal to be poured into the mold.

Figure 13 is a plane view of the sole plate of an iron in which the invention is employed.

Figure 14 is a cross-sectional view through the structure shown by Figure 13, taken substantially in the plane of line 14—14 thereon looking in the direction of the arrows.

Referring particularly to Figures 10 and 11, the numeral 10 indicates generally an electrically insulated resistance heating element or unit embracing the principles of the invention. In the embodiment of the invention shown by Figures 10 and 11 the unit 10 is formed in somewhat the shape of the sole plate of an iron except that the element 10 is somewhat smaller than the sole plate of an iron due to the fact that it is desirable to space the element within the sole plate structure in such a way that the unit will be located somewhat inwardly of the outer edges of the sole plate. The ends of the element 10 adapted to be disposed near the rear or unpointed end of the sole plate are turned inwardly as indicated at 11 and these are provided with upwardly projecting electrically insulated terminal blocks 12 and 13 from which the ends of the resistance wire 14 project. The pointed or front end of the element has an upwardly projecting support 16 for purposes to be hereinafter described. The unit 10 consists of a metallic armor or support 17, an electrically insulating sheath 18 and an electrical resistance member or wire 19 (see also Figures 1 to 9).

In forming the unit 10 there is employed a mold 21 having a channel 22 formed therein, the configuration of which is comparable to the plan view of the electrical resistance unit to be formed. In the present instance the plan view of the channel 22 will be the same as the plan view of the resistance unit 10 illustrated by Figure 10. The mold 21 comprises a lower movable part 23 which is disposed within the channel or cavity 22 for the purpose of supporting and measuring within

the cavity 22 the amount of electrical resistance material 26 required for making the upper section of the sheath 18. The upper section when completed is indicated by the numeral 24 in Figure 7. When the lower movable part 23 is held in the mold 21 in the position illustrated by Figure 1 the amount of loose insulating material which will exactly fill the mold to the top of the cavity 22 is the right amount for making the section 24 of the sheath 18.

In Figure 1 the lower movable part 23 of the mold 21 has an arcuate upper surface on which the arcuate armor 17 is positioned before the insulating material 26 is disposed and measured within the cavity 22. Flanges 28 formed at opposite ends of the armor 17 are adapted to receive the insulating terminals 12. Also the support 16 is secured in a flanged depression formed in the front or pointed part of the armor 17. The mold section 22 is of course recessed to fit and to support the terminals 12 and the support 16. Small openings indicated at 29 extend vertically through the terminal blocks 12 and communicate with clearance spaces 31 directly beneath the central portions of the terminals 12.

In order to compress the insulating material 26 upon the armor 17 a downwardly movable part or plunger 32 is employed (see Figure 2). The plunger 32 is shaped to conform to the configuration of the channel or cavity 22 and is provided at its lower end with an arcuate bead or projection indicated at 33 which is relatively concentric to the configuration of the insulating material supporting surface of the armor 17. Outwardly from each edge of the arcuate surface 33 are aligned planular surfaces 34 which are adapted to define a parting line between the lower and upper sections of the insulating sheath 18. Opposite the terminal blocks 12 the plunger 32 is provided with downwardly projecting punches 36 which are disposed in alignment with the openings 31 and which are adapted to form in the insulating material 26 openings for the resistance wire in alignment with the openings 31.

When the plunger 32 is applied to the insulating material as is illustrated in Figure 2 the lower movable part 23 of the mold 21 is moved downwardly against shoulders 37 adapted to support the part 23 in such a way as to receive the force applied by the plunger 32. The insulating material 26 is progressively compressed and compacted by the application of the plunger 32 until the thickness of the compressed and compacted insulating material is substantially equal in all directions between the arcuate surface 33 of the plunger 32, the supporting surface of the armor 17 and the sides of the cavity 22. When the plunger 32 is removed the insulating material 26 will remain compacted upon the armor 17 in such a manner that an arcuate channel or groove 38 will be formed in the upper part of the sheath section 24 by the bead 33 projecting from the lower surface of the plunger 32.

Figure 3 illustrates the next step in the process of forming the unit 10 in which a spirally wound electrical resistance element 41 is disposed within the groove or channel 38. The resistance element 41 is formed in such a manner as to have a curvature change greater than the curvature of the channel 38. In the instance illustrated by Figure 3 the element or wire 41 is spirally wound in such manner as to provide convolutions which appear as circles in cross-section, the radii of such circles being less than the radius of curva-

ture of the channel or groove 38. The opposite ends of the element or wire 41 are bent laterally in such a way as to extend through the terminal openings 29 and into the clearance space 31 beneath to provide the terminal wires 14, previously referred to. In order to measure the correct quantity of electrical insulating material 26 the lower movable part 23 is moved upwardly away from the supporting shoulders 37 into the position illustrated by Figure 3. Thereafter the cavity 22 is filled with the insulating material 26, such material being placed in the cavity 22 on top of the sheath section 24 and the spirally wound wire 41. The wire 41 is wound in such a manner that the convolutions thereof are separated far enough so that the insulating material 26 will fill the spaces within and between the convolutions of the wire 41.

Figure 4 illustrates the manner in which the insulating material 26 is compressed and compacted upon the previously formed section 24 of the sheath 18 to form a complete and integral unit of the sheath 18, the electrical resistance wire 41 and the armor 17.

To perform this step in the process there is employed a second plunger 42 similar to the plunger 32 except that the lower surface thereof employed in compressing and compacting the insulating material 26 is formed with a curvature similar to the curvature of the upper surface of the lower movable part 23 except opposite in relation thereto. When the plunger 42 is brought downwardly in the mold 21 the insulating material 26 is progressively compressed and compacted upon the sheath section 24 and the insulating material is also compressed and compacted upon the spirally wound wire 41. The force of compressing and compacting this insulating material upon the wire 41 tends to flatten each convolution of the wire, such compressing and compacting being continued until the wire 41 takes the shape indicated at 43 in Figure 8, in which oppositely disposed portions 44 of each convolution of the wire have approximately the same curvature as the channel 38. When the wire 41 has been compressed to this extent the thickness of the compacted insulating material surrounding the wire will be approximately equal in all directions normally with respect to each convolution of the wire.

After the unit 18 has been formed in this manner the plunger 42 is removed and the lower movable part 23 of the mold 21 is elevated as indicated in Figure 5 so that the composite and unitary element 10 can be removed from the mold.

After the unit 10 has been removed the unit may be embedded in fluid metal as, for example, in the casting process illustrated by Figure 12. Such process employs a mold 46 having relatively movable parts 47 and 48 formed of any suitable material and between which is provided a mold cavity 49 having a configuration comparable to any element which it is desired to make. The cavity 49 has a screw opening 51 through which in the present instance molten metal of any desired kind may be poured into the cavity 49. In the structure shown by Figures 12, 13 and 14 the cavity 49 is in the form of the sole plate of an iron, the upper surface 52 of the cavity being in the form of a planular surface roughly approximately the working or ironing surface of an iron, the lower surface 53 of the cavity corresponding to the upper surface of the

sole plate, while the side surfaces 54 of the cavity correspond to the side surfaces of the sole plate. It will be noted from Figure 12 that the unit 10 is disposed in the cavity 49 in such a manner as to be supported by the support 16 which is formed as a part of the armor 17 and by the two terminal blocks 12. The support 16 and terminal blocks 12 are disposed in openings formed in the part 47 of the mold 46 in such a manner that the support and terminals are held high enough within the cavity 49 that the armor 17 and flanges formed thereon around the support 16 and the terminals 12 do not engage the surface of the mold. Under such circumstances it will be apparent that when the cavity 49 is filled with molten metal the entire unit 10, including the armor 17 will be entirely embedded within the molten metal with only the support 16 and terminals 12 projecting therefrom.

After the molten metal is poured into the cavity 49 the entire mold is allowed to cool until such time as the parts 47 and 48 of the mold 46 can be separated and the finished casting indicated at 56 removed from the mold sections. Thereafter the metal of the casting 56 will continue to cool until the same is approximately at room temperature. During the entire process of cooling, the metal of which the casting 56 is formed will contract upon the unit 10 and will continue to further compress and compact the various elements of the unit 10 into a more composite unit and one in which the exterior surface of the sheath 18 will be brought into direct and intimate thermal contact with the metallic surface of the body of metal comprising the casting 56 and the interior surface of the armor 17.

By observing Figure 14 it will be noted that the thickness of the sheath 18 is substantially equal in all directions from the resistance wire 19 embedded therein, that the sheath 18 is in intimate thermal contact with the metallic body forming the casting 56 throughout a major portion of the exterior surface thereof and that such surface is adjacent the surface 52 which in the present instance is the working or ironing surface of the sole plate of an iron. Under such circumstances it will be apparent that the heat transfer rate from the resistance wire 19 will be substantially equal in all directions and particularly toward the ironing surface 52 and in which direction it is desired that heat shall be conducted in all directions at substantially a uniform rate.

Since heat will be conducted in all directions from the resistance wire 19 at a substantially uniform rate it will be apparent that no hot spots will develop in any portion of any convolutions of the wire 19 and consequently the wire 19 will not burn out readily.

The armor or shield 17, it will be noted from Figure 14, is disposed away from the ironing surface 52 and in which direction it is not desired to conduct heat at the maximum rate. However the shield or armor 17 will absorb heat from the wire 19 at substantially the same rate as the metallic casting surrounding the remainder of the sheath 18 and will conduct this heat transversely of the sheath in such a way that a considerable part of this heat will be delivered to the cast material on opposite sides of the unit and from whence the heat will be conducted by the cast body to the sole plate where it is desired to employ the heat.

While I have illustrated and described a preferred embodiment of my invention, it is understood that this is capable of modification, and I therefore do not wish to be limited to the precise details set forth, but desire to avail myself of such changes and alterations as fall within the purview of the following claims.

I claim:

1. A heating plate comprising a fused metallic body having electrical insulating terminals projecting therefrom, an electrical resistance heating element within said body and extending through and between said terminals, said heating element comprising a wire, a compressed sheath of dielectric material surrounding said wire and disposed between said wire and said body, the cross-sectional outline of said sheath being substantially oval shaped, said sheath being held under compression by said body in intimate thermal contact with said body and being substantially equal in thickness in all directions normally with respect to said wire between the longitudinal axis of said wire and the heating surface of said plate, and an arcuate shield secured to said sheath and in intimate thermal contact with said sheath and said body, said shield being positioned on the side of said sheath remote from said heating surface and having openings therein through which said terminals project.
2. A heating plate comprising a fused metallic body having a heating surface formed thereon, and an elongated electrical resistance heating element the cross-sectional outline of which is substantially oval shaped, cast within said body, said heating element comprising a spirally wound wire electrically insulated from said body, the electrical insulating material about said wire being of approximately equal thickness normally with respect to the convolutions of said wire, and an arcuate shield secured to said heating element along the surface thereof remote from said heating surface of said body.
3. A sole plate for irons comprising a fused metallic body having an ironing surface formed thereon, and an electrical resistance heating element cast within said body, said heating element comprising a spirally wound wire electrically insulated from said body, the convolutions of said wire having major and minor axes, said major axes being parallel to said ironing surface, and an arcuate shield secured to the insulating material about said wire along the surface thereof remote from said ironing surface, said insulating material and said shield being in intimate thermal contact with said body in all directions radially outwardly of said convolutions and between the longitudinal axis of said wire and said ironing surface.
4. A method of forming heating plates which comprises forming an electrical resistance heating wire to provide a heating unit having convolutions, compressing a segment of an electrical insulating sheath for said unit upon an elongated arcuate shield, forming a longitudinally extending groove in said segment, the radius of curvature of said groove being greater than the radius of curvature of said convolutions, disposing another segment of said electrical insulating sheath upon said first segment and said heating unit, compressing and compacting said unit in said groove and said other segment upon said unit and said first segment for completing said sheath about said heating unit, said compressing and compacting operation being continued until the radius of curvature of said convolutions of said

unit approximates the radius of curvature of said groove, embedding said sheath in fluid metal with said sheath directly engaging said fluid metal, and then extracting from said metal the heat of fusion of said metal for further compressing and compacting said insulating material upon said unit and in engagement with said metal during the contraction of said metal resulting from said extraction.

5. A method of forming sole plates for irons which comprises spirally forming an electrical resistance heating wire to provide a heating unit having convolutions of uniform radius of curvature, compressing a segment of an electrical insulating sheath for said unit upon an elongated arcuate shield, forming a groove in said segment, the radius of curvature of said groove being greater than the radius of curvature of said convolutions, disposing another segment of said electrical insulating sheath upon said first segment and said heating unit by compressing and compacting said unit in said groove and said other segment upon said unit and said first segment for completing said sheath about said heating unit, said compressing and compacting operation being continued until the radius of curvature of said convolutions of said unit approximates the radius of curvature of said groove and until said sheath is approximately equal in thickness in all directions normally with respect to the curvature of said unit, embedding said sheath in fluid metal with said sheath directly engaging said fluid metal, and then extracting from said metal the heat of fusion of said metal for further compressing and compacting said insulating material upon said unit and in engagement with said metal during the contraction of said metal resulting from said extraction.

6. A method of forming sole plates for irons which comprises spirally forming an electrical resistance heating wire to provide a heating unit having convolutions of uniform radius of curva-

ture, compressing a segment of an electrical insulating sheath for said unit upon an elongated arcuate shield, forming a groove longitudinally in said segment, the radius of curvature of said groove being greater than the radius of curvature of said unit, disposing said heating unit longitudinally in said groove, disposing upon said first segment and said heating unit another segment of electrical insulating material forming 10 said sheath, compressing and compacting said other segment thereon for completing said sheath about said heating unit, said compressing and compacting being continued until the radius of curvature of said convolutions of said unit approximates the radius of curvature of said groove, embedding said sheath in fluid metal with said sheath directly engaging said fluid metal and with the major axis of said heating unit in parallel relation to a planar surface, and then extracting 15 from said metal the heat of fusion of said metal for further compressing and compacting said insulating material upon said unit and in engagement with said metal during the contraction of said metal resulting from said extraction.
